COUPLER FOR MINIATURE RAILWAYS

John L. McKissock, Lake Worth, Fla.

Application May 24, 1946, Serial No. 672,132

2 Claims. (Cl. 213—88)

1

This invention relates to an improvement in couplers and has particular reference to couplers for use with the so called miniature railways to serve as draft connections between the locomotive and between the one or more cars that may be connected thereto.

The invention contemplates a coupler constructed in such manner as to serve as replacement for the standard couplers now furnished with the rolling stock on the miniature railways now in use and overcomes the many objections of the present manufactured couplers, such as inability to couple on curved track and the further objectional feature of the inability of such couplers to permit a sufficiently small radius turn without causing the coupler to become disengaged or a resultant derailment of the car.

An object of the invention resides in the provision of a coupler for connecting and disconnecting the adjacent ends of miniature railway cars either on a straight or curved track, such coupler constructed in such manner as to be yieldably mounted for flexing either laterally or vertically and further provides means engageable by a ramp for causing the couplers to be disconnected.

A further object of the invention resides in the extreme simplicity of the device, simulating in many respects the conventional couplers on modern railways and formed with an arm extension to be engaged by a ramp, such arm extension in appearance simulating a conventional air hose connection between cars.

Other and important objects of the invention will present themselves during the course of the following description, reference being had to the accompanying drawing, where:

Figure 1 is a side elevation of adjacent ends of two miniature railway cars, showing the invention in use and a track with an uncoupling ramp illustrated for engagement with the coupler.

Figure 2 is a plan view of the adjacent ends of the cars in uncoupled position.

Figure 3 is an end view of a car and an uncoupling ramp, with its operating means.

Figure 4 is a perspective view of a complete coupler unit and.

Figure 5 is a longitudinal section of the coupler, taken on line 5—5 of Figure 4.

Referring specifically to the drawings, wherein like numerals refer to like parts throughout, 5 designates the coupler as a whole, mounted upon the underside of each end of a railway car as shown in Figure 1. The couplers are identical

2

in each instance, being merely reversed at each end of the car. Two adjacent cars are indicated at 6 and 7, supported upon wheeled trucks 8 and 9, adapted to travel upon a conventional pair of rails 10.

Each coupler comprises a generally rectangular frame 11, open at top and bottom and formed with a flared forward end 12 to serve as a bumper and a connecting means for the adjacent coupler. The coupler is preferably formed of relatively thin sheet metal for ease in shaping and to minimize the cost of manufacture. The coupler is provided at its rear portion with a horizontal attaching flange 13, preferably stamped as an integral part of the frame and substantially flush with the upper edge of the frame. The flange is provided with a plurality of attaching screw holes 14, whereby the coupler unit may be conveniently secured in position upon the bottom of the car, as indicated. The flange portion 13 is provided with a down-turned ear 15, having a lug 16 bent therefrom at a right angle parallel to and toward one side of the frame 11. The lug 16 has soldered connection as at 16' with a close coupled coil spring 17, lying wholly within the frame and parallel therewith and to one side of said frame.

Soldered or otherwise permanently connected with the free end of the spring 17, as at 17' is a coupling member 18 of generally C-shape, projecting above and below the flared end 12 and forwardly thereof. The upper end of the member 18 is provided with a bevel end hook 19 for engagement with the flared end 12 of an adjacent coupler. The lower portion of the member 18 is formed in a relatively long curved portion 20 terminating in a rounded end 21, for engagement with an uncoupling ramp, to be described. The spring 17 is sufficiently stiff as to maintain the member 18 in proper coupling position at all times, but will permit ready shifting of the member 18 in a vertical direction for both coupling and uncoupling and laterally for freedom of movement to permit the cars to traverse short radius curves. The lateral flexing also permits the coupling of cars on curves, which has been impossible in couplers now in use.

The numeral 22 indicates generally an uncoupling ramp, comprising an elongated flat strip 50 having its ends curved downwardly, as at 23. The ramp is positioned parallel with and equidistantly spaced between the rails 10 and is supported for vertical movement upon a rod 24, held against turning by any suitable means. The rod 24 extends below the track bed and has pivotal connec-

tion with one arm of a bell-crank lever 25, pivoted to the underside of the track bed, as at 26. The other arm of the lever 25 may have connection with an operating cord or wire 27, whereby the operator may rock the lever 25 to raise and lower the ramp from a remote point. While a mechanical means has been illustrated to operate the ramp, it will be obvious that a suitable solenoid may be employed for causing the raising and lowering of the rod 24.

In use, identical couplers are attached to the ends of the rolling stock by the flanges 13, with the free ends of the coupler units projecting therebeyond. When it is desired to couple the cars, they are moved toward each other until the flared ends 12 engage the bevel ends of the coupler members 18, causing them to flex upward and ride over the edge of the ends 12 and snap their hooked ends therebehind. Should a coupling be made on a curved track, the member 18 at the shortest radius of the turn will engage first and, when the cars reach a straight track, the other member 18 will complete its engagement. The spring 17 permits freedom of turning movement of the cars without disengagement of the coupler and the slight spacing between the member 18 and the end 12 will afford some slight shock absorbing qualities in the starting and stopping of the train.

When it is desired to uncouple two or more cars, the operator spots the cars in question and when the forward end of the car in advance of the spotted car reaches and passes over the ramp 22, the cord 27 is pulled, causing the ramp to rise into the path of the rounded end 21 of the member 18 and when the coupler ends ride over the ramp, they cause the member 18 to move upward against the tension of the springs 17 for releasing the hooked ends 19 from their respective bumpers 12, after which the ramp is permitted to drop by gravity to assume its inoperative position.

It will be seen from the foregoing that an extremely simple and efficient type of coupler has been provided for miniature railways. The coupler is strong, durable, cheap to manufacture and highly efficient in use.

It should be understood that the invention is not limited to the precise arrangement shown, but that it includes within its purview, whatever changes fairly come within either the terms or the spirit of the appended claims.

Having described the invention, what is claimed is:

1. A coupler for miniature railway cars comprising a rectangular frame, open at top and bot-

tom, said frame provided with a flared forward bumper end, attaching flanges formed upon the rear end of the frame, a coupler member arranged in the frame and projecting above and below the frame and forwardly of the bumper end, a coil spring connected with the coupler member and with the rear portion of the frame, said spring lying wholly within the frame and to one side thereof, said coupler member provided with a bevel engaging hook at its upper free end and a curved ramp engaging portion at its lower free end, said spring permitting vertical and lateral movement of the coupler member for coupling engagement and disengagement to and from a co-acting coupler and a ramp movable into and out of the line of travel of the lower free end of the coupler member.

2. A coupler for miniature railway cars comprising a rectangular flat walled frame having a flared forward bumper end, horizontal attaching flanges formed integral with the rear portion of the frame, a right-angled attaching lip bent from the flange and lying within the open rear end of the frame, a lug formed upon the lip, a coiled spring permanently attached to the lug and arranged within the frame parallel thereto and to one side thereof, a coupler member arranged within the frame and permanently connected to the forward end of the spring, said coupler member formed of generally C-shape and projecting above and below the frame and forwardly of the bumper end, said coupler member provided with a bevel hook at its upper free end and a curved ramp engaging portion at its lower free end, said bevel hook lying in the path of travel of the bumper end of a co-acting coupler, a ramp movable into and out of the path of travel of the lower curved end of the coupler member and means for controlling the ramp.

JOHN L. McKISSOCK.
